220,363

LAMINATING APPARATUS OR SIMILAR ARTICLE

Henry N. Staats, Deerfield, Ill., assignor to General Binding Corporation, Northbrook, Ill.

Filed Nov. 13, 1969, Ser. No. 20,061

Term of patent 14 years

Int. Cl. D15—05

U.S. Cl. D55—1

FIG. 1 is an isometric view of the laminating apparatus; FIG. 2 is a top plan view thereof; and

FIG. 3 is a front elevational view thereof, it being observed that the rear elevational view is substantially identical thereto.

I claim:

The ornamental design for a laminating apparatus or similar article, as shown and described.
